UNITED STATES PATENT OFFICE

FRANTIŠEK JERMÁŘ, OF OPAVA, CZECHOSLOVAKIA

WEIR SHUTTER

Application filed June 27, 1930, Serial No. 464,403, and in Czechoslovakia April 26, 1930.

The object of the present invention is to produce a hydrostatic weir shutter which presents a comparatively narrow structure as compared with the vertical adjustability of the shutter and which will operate without auxiliary mechanisms, and the invention consists in mounting two arcuate leaves at opposite sides of a sub-structure so as to overlap across the latter, the leaves being provided at their free ends with rollers whereby each leaf is guided on and abuts against the other.

Fig. 1 of the accompanying drawing represents a cross-sectional view of the shutter, and

Fig. 2 is a cross-sectional view showing the leaves slightly modified in form.

The shutter comprises a sub-structure 5 provided with a well across which two arcuate leaves 1 and 2 overlap, the leaves being hinged at 3 and 4 respectively to opposite sides of the sub-structure. An orifice at the bottom of the well communicates through a channel 12 with the high and through a channel 13 with the low water. One channel is provided with a valve 10 and the other with a valve 11 whereby either communication can be cut off. When the valve 11 is closed and the valve 10 opened water enters the well from the high water side and raises the shutter. When the valve 10 is closed and the valve 11 opened, the water leaves the well and allows the shutter to drop.

The leaf 1 is extended beyond the flange 3, and the extension 6 limits the upward movement of the leaves by abutment against a shoulder 9 on the sub-structure. The latter is formed with a chamber 14 whence the valves can be operated.

In the lowermost position 1' and 2' of the leaves, the leaf at a lower water side covers the orifice of the water channel and supports on its outer surface, substantially mid-way between the ends, the free end of the companion leaf. It will therefore act with a considerable leverage on the companion leaf at the initial and most difficult stage of raising the shutter. The raising of the leaves from this position is still further facilitated by the action of the overflowing water on the extension 6 of the leaf 1.

In an intermediate position, 1'' and 2'',

of the leaves, the overlapping portions of the latter lie flat against each other, and in the upper positions of the leaves, the leaf 2 bears with its inner surface against the free end of the leaf 1.

55

The leaves 1 and 2 are fitted at their free ends with anti-friction rollers 7 and 8 respectively which take the thrust.

It will be observed that the hinges 3 and 4 are arranged on substantially the same level and that the leaves form together a substantially unbroken surface over which lumps of ice and the like can pass without setting up detrimental shocks.

The leaves may either be uniformly 65 curved as shown in Fig. 1, or bent at an angle as shown in Fig. 2.

I claim:

1. A hydrostatic weir shutter comprising a substructure having a well and a channel which opens at the bottom of the well and communicates with the high as well as with the low water, valves for closing either communication, two arcuate leaves, equally long and symmetrical hinged, at points situated on the same level, to opposite sides of the structure and overlapping across the well, the leaf at the low water side being adapted, in its lowermost position, to rest with its free end against the bottom of the well and cover the channel orifice, and anti-friction rollers connected to the free ends of both leaves as guide and thrust elements, the leaf at the high water side being adapted to bear with its free end against the outer surface of the companion leaf in the lower position of the shutter and with its inner surface against the free end of the companion leaf in the upper position thereof.

2. A weir shutter as claimed in claim 1 80 wherein the leaf at the low water side of the structure is extended beyond the hinge and adapted, by abutment against the sub-structure, to limit the upward movement of the leaves.

FRANTIŠEK JERMÁŘ.
